UNITED STATES PATENT OFFICE.

RICHARD F. HODGE, OF INDIANAPOLIS, INDIANA.

DIRECTION-INDICATOR FOR MOTOR-CARS.

1,283,186.

Specification of Letters Patent. Patented Oct. 29, 1918.

Application filed February 13, 1917. Serial No. 148,356.

To all whom it may concern:

Be it known that I, RICHARD F. HODGE, a citizen of the United States, residing at Indianapolis, in the county of Marion and State of Indiana, have invented certain new and useful Improvements in Direction-Indicators for Motor-Cars, of which the following is a specification.

This invention relates to a combined head, tail and direction indicator light for motor cars; and one of the objects of the invention consists in the provision of means whereby an operator of a motor car can display, on any part of his car from the steering wheel, certain signals indicating to other motor car operators, and to pedestrians, the course he intends to pursue after his signal is displayed.

A further object of the invention consists in certain means whereby, at the time the direction signal is displayed, the permanent head light and tail light are extinguished, so as to prevent confusion on the part of others through the blending of the rays of a plurality of simultaneously exposed lights.

The above objects of the invention, and such others as may appear from a perusal of the specification and claims, are attained by means of the construction illustrated in the accompanying drawings, forming a part hereof, in which—

Figure 1 is a side elevation of my improved direction indicator lamp. Fig. 2 a front elevation of the lamp. Fig. 3 a longitudinal central sectional view of the lamp, on the line 3—3 in Fig. 2. Fig. 4 is an enlarged cross sectional view of the lamp, on the line 4—4 in Figs. 1 and 3. Fig. 5 is a partial side elevation of the collar surrounding the middle portion of the lamp.

Referring to the drawings, it will be observed that the direction indicator contemplates a structure provided with a forward and rearward projected lens, in order that the customary white head light in front and rear red light can be preserved in connection with the added direction indicators for front and rear display. The lamp comprises a thin metal shell 10, preferably of a shape shown in Fig. 1, being somewhat contracted in diameter at its longitudinal center. The lenses of the lamp are retained in position in the ends of shell 10 by means of the usual rim-bands 12. Shell 10 is divided lengthwise to provide the chambers 14, 15 and 16 by means of the horizontally disposed par-

titions 18 and 19. An electric lamp 20 is projected into chamber 14 through the central and contracted wall of shell 10 (see Fig. 4) and illuminates the interior of shell 10 down to partition 18. The front lens A is transparent and free from coloration down to a line parallel with partition 18 so that the rays of light are projected forward free from interference for observation purposes. The rear lens B down to a line parallel with partition 18 is usually colored red in order to display the customary danger signal toward the rear. Central chamber 15 comprises the space within the vertical limits of partitions 18 and 19 and is illuminated by means of an electric lamp 25, and lenses A and B between lines which are parallel with the ends of partitions 18 and 19 are rendered opaque with the exception of the indicia (here shown as an outline of a human hand) which are left transparent for indicating the course into which the operator intends to direct his vehicle. Lower chamber 16, between partition 19 and the wall of shell 10, is illuminated by means of an electric lamp 27, and lenses A and B between lines parallel with the ends of partitions 19 and their lower edges are rendered opaque with the exception of the indicia thereon which are left transparent, similar to the positions of the lenses extending across the ends of chamber 15. The indicia on the lower sections of lenses A and B are arranged to point in the opposite direction from those shown on the central portions of said lenses.

In view of the location of lamps 20, 25 and 27, the connecting wires must of necessity be carried around a portion of shell 10, and in order to provide a neat appearing device, I remove from view all of the wires leading to the several lamps and inclose them in a suitable conduit, instead of allowing them to be exposed as shown in Fig. 4 which is merely a diagrammatic arrangement of the wiring for imparting a clearer understanding of the invention. The means employed for inclosing the wires leading to the several lamps comprises an annular collar 70 which extends circumferentially around shell 10. Collar 70 is formed rectangular in cross section with its outer periphery and sides closed, thereby providing an annular channel 72 forming a passageway for the wires leading to lamps 20, 25 and 27. Collar 70 is preferably formed in two sections, as shown in Fig. 5, which are held together

by means of the screws 74, thereby enabling said collar to be easily placed in and removed from operative position.

Having thus fully described my said invention, what I desire to secure by Letters Patent, is—

1. A direction indicator for motor cars comprising a hollow structure open at opposite ends, means for longitudinally dividing said structure into compartments, a lens for closing each open end of said structure, and a hollow collar extending circumferentially around said structure, said collar providing a bearing for supporting the illuminating lamps and for inclosing the wires leading to said lamps.

- 15

2. A direction indicator for motor cars comprising a hollow structure open at opposite ends, means arranged in said open ends for mounting indicia, means for longitudinally dividing said structure into compartments, an open two part hollow collar extending circumferentially around said structure, said collar providing a bearing for mounting the illuminating lamps and for inclosing the wires leading to said lamps.

In witness whereof I have hereunto set my hand and seal at Indianapolis, Indiana, this 26th day of January, A. D. one thousand nine hundred and seventeen.

RICHARD F. HODGE. [L. S.]
